SPINNING RESERVE WITH INLET THROTTLING
AND COMPRESSOR RECIRCULATIONRobert L. Hendrickson, Scotia, N.Y., assignor to General
Electric Company, a corporation of New York
Filed Dec. 15, 1965, Ser. No. 513,929
5 Claims. (Cl. 290—2)

This invention relates generally to the use of gas turbine-generator units as reserve power units in power generation stations. In particular, this invention relates to an improved standby power generation capacity using gas turbine-generators in "spinning reserve."

Electric power systems require blocks of capacity to be held on standby to protect the system against a forced outage of a main generating unit. This standby capacity must be capable of developing full load in a matter of seconds after a forced outage occurs and should therefore be warmed up and running at normal operating speed, ready to assume a load. This running standby capacity is known as "spinning reserve." The problem that it presents is in providing this reserve capacity at minimum cost.

It has been proposed in the past to employ steam turbine generators for this purpose, using the generator as a motor to keep the unit up to speed and putting into the turbine only enough steam to maintain the turbine parts at temperatures approximating their operating temperatures to avoid thermal shock when the unit is called upon to carry load. This is no longer practical simply because the costly reheat steam units in present-day powerplants cannot be economically regulated to standby duty.

The power developed in the turbine element of a gas turbine is used in two ways. First, it goes to drive the compressor and the remainder goes into useful output which, for purposes of illustrating this invention, will be considered to be a generator. A generator must be driven at constant speed as, for example, 3600 r.p.m., regardless of the load on the generator. This means that the gas turbine and hence its compressor, which is either on the same shaft or geared to the generator shaft, are rotating at full speed regardless of the power level. Without modification, the compressor would be taking in the same amount of air at all power levels, absorbing a higher fraction of the turbine output as the load is reduced. This leads to relatively high fuel consumption at low power output. In order to reduce the flow of air through a gas turbine combustor when the turbine is running at lower power levels, it is known that a throttling of inlet air to the compressor will permit a reduction of fuel consumption. It is also known that air flow through the combustor of a gas turbine can be reduced, and hence fuel saved at lower power levels, by extracting compressor air and recirculating it to the compressor inlet or to a lower compressor stage, so that the combustor receives air flow equal to the difference of air inlet flow and air recirculation flow.

When compressors are operating under certain conditions of mass flow, pressure ratio and rotational speed, they become subject to the phenomenon known as surging; that is, the fluid which normally flows a predictable path through the compressor becomes unstable causing the pressure to fall considerably. The relationship of the above parameters is such that at a given speed, surging is more likely to occur at higher compression ratios, or higher discharge pressures, and lower mass flows through the compressor. It can be seen, then, that throttling by reducing mass flow, tends to cause the gas-turbine compressor to reach its surge limit. However, if the compressor discharge is partially recirculated to the compressor inlet, the result is a lower compression ratio and lower compressor discharge pressure. Thus, though mass flow is decreased by inlet throttling, pressure ratio and discharge

2

pressure are also decreased and surging is avoided. Therefore, with the combined effect of recirculation, compressor inlet can be throttled to an extent greater than would be possible without the recirculation.

5 The object of this invention is to provide a means and method whereby a gas turbine can be run at operating speed and temperature with minimum load, no load, or even at negative load (absorbing power from the generator) with a minimal fuel consumption, and be ready for duty on a moment's notice.

10 Other objects, advantages and features of this invention will become apparent from the following description taken in connection with the accompanying drawing.

Briefly stated, the essence of this invention includes a 15 gas turbine-generator unit, connected on the line of a power generation system. The generator takes power from the system and thus, as a motor, is the prime mover of the unit. The gas turbine air intake is throttled and the compressor air extracted and recirculated to the intake to provide minimum air flow to the combustor and hence minimum fuel consumption. The recirculated compressed air provides higher air temperature to the combustor for better combustion. The gas turbine has thus been relieved of its mechanical load, and is being carried by the generator-motor. The combustor is burning a minimum of fuel with less air flow, primarily for the purpose of maintaining operating temperatures in the turbine.

In the drawing:

FIG. 1 is a schematic representation of a gas turbine-generator unit according to this invention.

30 FIG. 2 is a curve of turbine efficiency as a function of blade velocity and gas nozzle velocity.

Referring now to FIG. 1 for the purpose of illustrating this invention, a gas turbine-generator unit is shown comprising a compressor 1, a combustion chamber or combustor 2, a gas turbine 3 and a dynamoelectric machine or generator 4 connected to a power system represented as 5. In this arrangement and under normal operating conditions, air is admitted through an inlet conduit 6 to the compressor 1 where it is compressed and delivered through connecting conduit 7 to the combustor 2. Fuel enters the combustor 2 through conduit 8. The air and fuel are burned in combustor 2 to produce hot gas which flows through conduit 9 to the turbine 3, exhausting through conduit 10 to atmosphere. The turbine converts the thermal energy of the gas to mechanical energy to drive the compressor 1 and the generator 4. Turbine 3 and compressor 1 are connected to a common shaft 11. Turbine 3 and generator 4 are in turn connected to a common shaft 12. Shafts 11 and 12 are connected to each other. That is to say, turbine 3 is of the "single shaft" type in which compressor, turbine, and external load occupy the same shaft.

55 The foregoing has been descriptive of a typical gas turbine-generator unit under normal operation. It will be understood that while a single combustor and conduit system has been shown, there may be several of them arranged around the turbine shaft. Also it will be understood that while the generator is shown direct-connected to its driving turbine, there may be reduction gears between the turbine and the generator.

In addition to the basic structure of a gas turbine plant as described above, there is included in the turbine-generator unit of this invention an inlet throttle valve 13 in the inlet conduit 6. A recirculation line 14 which includes a recirculation control valve 15 connects a high pressure section of the compressor 1 to the inlet conduit 6 at a point between inlet throttle valve 13 and the inlet to compressor 1. Though not shown, it is also possible to have recirculation line 14 enter the compressor 1 at a low pressure stage in the compressor other than the compressor inlet.

The operation of the present invention will now be described, using the above-described normal operation as a frame of reference. The power normally required to be developed in the turbine is not required when used in its spinning reserve mode according to this invention. The power ordinarily required to drive the generator 4 is not required since the generator is being driven as a motor on the system 5. The power ordinarily required to drive the compressor is greatly reduced because (1) free air is being throttled by valve 13, and (2) hot, pressurized air is being recirculated through conduit 14 to the compressor inlet. Air flow through the combustor is reduced by (1) the amount of compressor recirculation, (2) the reduced inlet pressure provided by the throttle, and (3) the increased temperature provided by recirculating the hot pressurized air, thus permitting efficient combustion with less fuel. The higher air temperature resulting from the compressor recirculation due to heating of the air during compression, provides improved combustion and therefore still further fuel economy. The combined effects of inlet throttling and compressor recirculation are to permit a minimum of fuel to increase the turbine temperatures to substantially their full load or normal operating values, thus reducing or eliminating thermal shock that would otherwise result from a rapid increase to full load temperatures.

FIG. 2 is a curve of the engine efficiency of a pure impulse turbine. It is not intended to define limits within this invention but rather as a representation of the operation of the invention for purposes of graphic illustration. Engine or turbine efficiency is the ratio of actual work to ideal work performed by an ideal engine using the same fluid. The independent variable plotted on the abscissa is the variable ratio W/V_0 where W is the turbine blade tip velocity and V_0 is the velocity of the turbine nozzle fluid. A pure impulse turbine reaches its peak engine efficiency where the blade speed W is half the speed of the working fluid. As can be readily visualized and as the curve shows, there is no turbine output when the blade and working fluid are moving at approximately the same speed. The continuation of the curve where engine efficiency is negative and W/V_0 is greater than one (blade tip moving faster than working fluid) is representative of the case where the turbine is being driven by the generator, absorbing energy from the electrical system instead of putting energy into it.

The presently preferred arrangement of this invention is to have the unit operating somewhere in the range labeled "B" on FIG. 2. This means that more power is being absorbed from the system 5 and less fuel is being burned than in the "A" range. This is presently preferred because it is more economical to draw electrical energy from the system for spinning than to consume the higher cost gas turbine fuels.

Typical values for inlet throttling are in the approximate range of $\frac{1}{4}$ to $\frac{1}{5}$ atmospheres pressure at the compressor inlet. Recirculation of the compressor air is preferably in the range of 20-45 percent. The optimum spinning operation of a gas turbine will be a function of a particular combination of these two variables which in turn is dependent upon the characteristics of individual gas turbine components and their fuels. The best combination occurs when each of the following conditions is met:

- (1) Maximum turbine temperature,
- (2) Minimum compressor surge margin,
- (3) Minimum combustion temperature rise,
- (4) Minimum combustor air flow,
- (5) Minimum fuel consumption in the combustor.

It will occur to others skilled in the art to make experiments guided by the foregoing to arrive at optimum conditions for a particular unit.

In another modification of this invention, it is possible to use a gas turbine of "two-shaft" type. That is to say, that shafts 11 and 12 are separate and the turbine is a gas turbine with a plurality of stages, in effect, two separate turbines within the common casing, one being connected to and driving the compressor, and the other being connected to the generator. In this modification the generator drives the lower stage turbine, but the compressor turbine is maintaining compressor speed, requiring at least a minimum of power and therefore more fuel consumption as compared to the first-described system in which fuel is burned but no power derived therefrom.

Thus, it will be apparent that a gas turbine-generator unit has been described which will operate at a minimum or a negative power output and at operating speed and temperature in order to be ready to assume load and produce full power in seconds. Furthermore, it will be apparent that this spinning reserve capacity is produced with relative economy, both from the minimum fuel burned and from the lower initial cost of a gas turbine plant.

It will occur to others of ordinary skill in the art to make modifications of this invention which will remain within the concept and scope thereof and will not constitute patentable departure therefrom. Accordingly, it is intended that the invention be not limited by the details in which it has been described but that it encompasses all within the purview of the following claims.

What is claimed is:

1. A heat engine operatively connected to a dynamo-electric machine, said dynamo-electric machine connected to an electric power system, said heat engine comprising an air supply conduit, an air compressor, a fuel source, a combustor to combine fuel and air for combustion, a gas turbine into which the products of said combustion expand, means to throttle the intake of air through the supply conduit to said heat engine, and means to extract pressurized air from said compressor and recirculate it to a lower pressure part thereof, so that said combustor receives air flow equal to the difference of air inlet flow and air recirculation flow.

2. A method of operating a gas turbine-generator, which is connected to an electric power system, in standby reserve comprising:

- (a) driving said turbine at a speed substantially corresponding to generator synchronous speed using said generator as a motor,
- (b) throttling compressor inlet air to reduce air flow through said turbine,
- (c) extracting compressor air from a point of relatively higher temperature and pressure,
- (d) recirculating said extracted compressor air to a lower pressure part of said compressor, further reducing air flow through said turbine.

3. The method described in claim 2 further including the step of burning fuel in the combustor of said turbine in the presence of air from said compressor.

4. The method according to claim 2 wherein the inlet throttling is such as to provide $\frac{1}{4}$ to $\frac{1}{5}$ atmospheric pressure at the compressor inlet and wherein the recirculated air is between 20 and 45 percent of total air flow through the compressor.

5. The method according to claim 2 including the step of burning fuel in the combustor and adjusting the extent of air throttling and extent of air recirculation with respect to one another to provide minimum fuel consumption at a selected turbine operating temperature.
